UNITED STATES PATENT OFFICE.

CHARLES J. WHITE, OF NEW BRITAIN, CONNECTICUT, ASSIGNOR TO THE C. J. WHITE MFG. CO., OF NEW BRITAIN, CONNECTICUT, A CORPORATION OF CONNECTICUT.

DESIGN FOR A GARTER.

48,138.

Specification for Design.

Patented Nov. 9, 1915.

Application filed July 30, 1915. Serial No. 42,837. Term of patent 14 years.

To all whom it may concern:

Be it known that I, CHARLES J. WHITE, a citizen of the United States, residing at New Britain, Hartford county, Connecticut, have invented a new, original, and ornamental Design for a Garter, of which the following is a specification, reference being had to the accompanying drawing, forming part thereof, in which the new design is shown by a single perspective view.

I claim:

The design for a garter as shown.

CHARLES J. WHITE.
